Primary Examiner — Robert A Delehanty*(74) Attorney, Agent, or Firm* — Foley & Lardner LLP(57) **CLAIM**

We claim the ornamental design for a faucet, as shown and described.

DESCRIPTION

FIG. 1 is a perspective view of an embodiment of the claimed design;
FIG. 2 is a front view of the embodiment of FIG. 1;
FIG. 3 is a rear view of the embodiment of FIG. 1;
FIG. 4 is a side view of the embodiment of FIG. 1;
FIG. 5 is another side view of the embodiment of FIG. 1;
FIG. 6 is a top view of the embodiment of FIG. 1;
FIG. 7 is a bottom view of the embodiment of FIG. 1;
FIG. 8 is a perspective view of another embodiment of the claimed design;

FIG. 9 is a front view of the embodiment of FIG. 8;
FIG. 10 is a rear view of the embodiment of FIG. 8;
FIG. 11 is a side view of the embodiment of FIG. 8;
FIG. 12 is another side view of the embodiment of FIG. 8;
